C. V. LOGWOOD

OSCILLATING CURRENT SYSTEM

Filed May 28, 1921

Patented Nov. 24, 1925.

1,562,569

UNITED STATES PATENT OFFICE.

CHARLES V. LOGWOOD, OF NEW YORK, N. Y.

OSCILLATING-CURRENT SYSTEM.

Application filed May 28, 1921. Serial No. 473,863.

To all whom it may concern:

Be it known that I, CHARLES V. LOGWOOD, a citizen of the United States, residing at New York, county of Bronx, and State of New York, have made a certain new and useful Invention in Oscillating-Current Systems, of which the following is a specification.

This invention relates to oscillating current systems, and is especially adapted for use in connection with radio frequency oscillations systems such as are used in radio communications for the transmission and reception of signals.

15 The object of the invention is to provide a system which is simple in structure, efficient in operation, and wherein the power obtained from alternating current generators, particularly of the vacuum tube type, 20 may be greatly increased.

Further objects of the invention will appear more fully hereinafter.

The invention consists substantially in the construction, combination, location and relative arrangement of circuits and electrical instrumentalities employed in connection therewith and the method utilized, all as will be more fully hereinafter set forth as shown by the accompanying drawing and 30 finally pointed out in the appended claims.

Referring to the drawing,—

Fig. 1 is a diagrammatic view of the wiring diagram embodying the principles of my invention;

35 Fig. 2 is an enlarged detail diagrammatic view showing the type of transformer employed in accordance with my invention;

Fig. 3 is a diagrammatic view of the characteristic curve of the thermionic type of 40 oscillator or generator.

The same part is designated by the same reference character wherever it occurs throughout the several views.

While I have shown and will now describe my invention as particularly applied to a radio transmitting station, whereby the principles of my invention may be readily understood, I wish it to be borne in mind that I do not desire to be limited or restricted to this particular application of my invention, as the same may be utilized in various other uses such as for reception of a radio signals as an amplifier or for a relay for alternating currents irrespective of whether or not they be of audio or radio frequency. The essence of the invention is that by suitable

circuit arrangements amplification of an enormous extent is obtained, and it will be apparent to those skilled in the art that while, as above stated, I have selected amplification of oscillating current energy at a transmitting station to illustrate the principles of my invention, its applicability to other use will be at once seen.

Referring to the drawing, 1 designates the antenna which is connected to earth through the usual inductance through the primary condenser 4, and, if desired, the ammeter 5. One terminal of the inductance 3 is adjustably connected to the plate electrode 6 of audion 7. The grid electrode 8 of audion 7 is connected through condensers 9 and 10 to the grid electrode 11 of audion 12. The grid electrodes 8 and 11 are likewise connected together through choke coils 13 and secondary winding 14 of a modulation transformer. The primary coil 15 of the modulation transformer is included in the circuit preferably containing an inductance coil 16, a source of current 17, and the signal switch 18. Or, if desired, it may be included in the circuit containing current source 19, and a microphone 20, all depending upon whether it is desired to utilize the transmitting system for telegraph or telephone. The filament electrodes 21 of the audions 7 and 11, are in this instance connected in parallel, and are lighted from a suitable current source 22, controlled by an adjustable rheostat 23. From the approximate center of the secondary coil 14 of the modulation transformer I connect a high resistance element 25. 26 designates the usual B battery which in this instance is shown as a direct current machine. The current passes from the positive terminal of the direct current machine to the middle of the two coils of the transformer generally designated 27, and through the coil 28 thereof through choke coil 29 to the plate electrode 30 of audion 12. The other path of travel of current from the positive terminal of the generator 26, is through the coil 31 of transformer 37, choke coil 32, to the plate electrode 6, of audion 7. The two windings 28 and 31 are so wound that the fields thereof are opposed to each other as long as the current is flowing freely in both coils 28 and 31. It will, therefore, be obvious that if the circuit was oscillating, that both of the plate electrodes of the audions 7 and 12 would deliver their energy at the

same rate and at the same frequency because the grid electrodes 8 and 11 would be changing their potential at the same time and at the same frequency, and this would be true even if the plate electrode 6 of audion 7 were the only one that is in an oscillating circuit.

If, for a given instant, the impulse from the modulation transformer 15, 14, is positive, it would put a positive charge on the grid electrode 8 of audion 7. This would cause a slight increase of current through the plate electrode 6 thereof at the same time the negative impulse was impressed on the grid electrode 11 of audion 12. This would cause a big drop in the current of the audion 12. Then the voltage would build up in the coils 43, 44, of the transformer 27, which are connected at their mid point through a condenser 45 to the filaments 21, and are wound opposed to each other similarly, as in the case of coils 28 and 31, and have their terminals connected respectively to the plate electrodes 30 and 6. Due to the voltage building up in the windings 43 and 44, the condenser 45 becomes charged. By means of this arrangement it will be apparent that the negative impulse caused by the induced current in the winding 44 to add to the plate electrode 6, thereby serves to add still further to the slight increase of the plate current as when the grid 8 of audion 7 was charged positive. It will be apparent that the result is an addition to the radiation which is secured, and it will further be apparent that a discharge of the condenser 45 further increases this addition. The next reversal of the impulses in the modulation makes the radiation drop because this time the grid electrode 11 of audion 12 is made positive, and the slight increase of the plate current will not make as much change of potential as the negative charge 6. When the negative charge on the grid 8 of audion 7 causes a big drop of current through the audion 7, this tends to build up a potential on the plate electrode 30 of audion 12, by a sudden change of current through the plate 6 of audion 7, which induces currents in the windings of the transformer 27 as hereinbefore described. The building up of current in the audion 12 does not affect the radiation, as will be apparent, because the audion tube 7 is the only tube employed which is in the oscillating circuit. The function of the resistance leak 25 is to allow the collecting negative charge on the grid electrodes 8 and 11 to leak off to the filament. The characteristic curve of the modern power tube as illustrated in Fig. 3 shows that the plate current grid voltage when plotted has a steep rise in the plate current on the negative half of the cycle to one half of the saturation current. The curve then flattens

out until the positive half of the cycle is far beyond on the positive half, so that the change of potential of the modulation transformer has little effect upon the characteristic current.

70

While I have described what at the present time appears to me to be the theoretical explanation of the operation of the system of my invention, I do not advance the same as being the only explanation which can be advanced, and I therefore, desire to have the foregoing discussion of the theory of operation regarded as an effort to advance one theory of operation which will permit the circuit employed to be understood.

80

As hereinbefore mentioned, the transformer 27 requires as its essential elements the opposed windings 28, 31 and 43, 44, and while I have shown an especially constructed transformer, and will now proceed to describe the same in detail, I do not desire to be limited or restricted to such special construction.

85

The core of the transformer illustrated at 50 is preferably made of laminated pieces, and may or may not be a solid closed magnetic circuit. In practice I prefer to employ an air gap as illustrated, or at least an open core. I also prefer to employ one to one ratio. Each of the transformer coils has about two thousand turns of insulated wire arranged, in layers, each layer insulated from its adjacent layer, for example, by oil paper, so as to protect the windings from the high potentials which surge in the coils. The size of the wire employed depends upon the current load. It will be apparent that the function of the transformer is to react in such a way that whenever one of the tubes 7, 12, in the circuit is robbed of its current, the induced currents in the other windings assist the currents of the other tubes.

190

Referring again to Fig. 1, the impedance coil 52 and the condenser 53 employed in the circuit, including the current source 26, are used for smoothing off the ripples in the circuit in which a commutator is located.

105

Many modifications and changes in detail will readily occur to those skilled in the art without departing from the spirit and scope of my invention. Therefore, having shown and described a structure embodying the principles of my invention, and having set forth the objects and nature thereof, what I claim as new and useful and of my own invention and desire to secure by Letters Patent is:

115

1. An oscillation generator system comprising two audions having the plate electrodes thereof connected in parallel, an oscillating circuit operatively associated with the plate electrodes of said audions, a circuit including a source of current connecting said plate electrodes and the filament

120

125

electrodes of said audions, and means for alternately charging alternate grid electrodes of said audions positively and negatively.

- electrodes of said audions, and means for alternately charging alternate grid electrodes of said audions positively and negatively.

5. 2. An oscillation generator system comprising two audions having the plate electrodes thereof connected in parallel, an oscillating circuit operatively associated with the plate electrodes of said audions, a circuit including a source of current connecting said plate electrodes and the filament electrodes of said audions, and means controlled by a signal to be transmitted for alternately charging alternate grid electrodes of said audion positively and negatively.

10. 3. In an oscillating audion transmitting system, two audions with their plate electrodes connected in parallel, a common signalling device associated with the grid electrodes of both audions, a common source of current supply for said plate electrodes, and an impedance coil included in circuit with said source of current supply, one of said plate electrodes being connected to one portion of said impedance coil and the other of said plate electrodes being connected to the other portion of said impedance coil, and an oscillatory circuit operatively associated with the plate electrodes of said audions.

15. 4. The combination with a plurality of electrically connected audions and their associated circuits, a source of current connected to the plate electrodes of said audions, an impedance coil interposed between the source of current and each plate electrode, the impedance coil of each plate electrode being wound in opposition to its adjacent impedance coil of the plate electrode of adjacent audions, and an oscillatory circuit operatively associated with the plate electrode of only one of said audions.

20. 5. The combination with a plurality of electrically connected audions and their associated circuits, a source of current connected to the plate electrodes of said audions, an impedance coil interposed between the source of current and each plate electrode, the impedance coil of each plate electrode being wound in opposition to its adjacent impedance coil of the plate electrode of adjacent audions, a signalling device associated with the grid electrodes of said audions, and an oscillatory circuit operatively associated with the plate electrode of only one of said audions.

25. 6. The combination with a plurality of electrically connected audions and their associated circuits, a source of current connected to the plate electrodes of said audions, an impedance coil interposed between the source of current and each plate electrode, the impedance coil of each plate electrode being wound in opposition to its adjacent impedance coil of the plate electrode of adjacent audions, and an oscillatory circuit operatively associated with the plate electrode of only one of said audions.

30. 7. The combination with a plurality of electrically connected audions and their associated circuits, a source of current connected to the plate electrodes of said audions, an impedance coil interposed between the source of current and each plate electrode, the impedance coil of each plate electrode being wound in opposition to its adjacent impedance coil of the plate electrode of adjacent audions, a divided impedance coil with the divided portions thereof wound in opposition to each other, each division thereof interposed in circuit between the source of current and the filament electrodes of said audions, and an oscillatory circuit operatively associated with the plate electrode of only one of said audions.

35. 8. The combination with a plurality of electrically connected audions and their associated circuits, a source of current connected to the plate electrodes of said audions, an impedance coil interposed between the source of current and each plate electrode, the impedance coil of each plate electrode being wound in opposition to its adjacent impedance coil of the plate electrode of adjacent audions, a telephone transmitter associated with the grid electrodes of said audions, and an oscillatory circuit operatively associated with the plate electrode of only one of said audions.

40. 9. The combination with a plurality of electrically connected audions and their associated circuits, a source of current connected to the plate electrodes of said audions, an impedance coil interposed between the source of current and each plate electrode, the impedance coil of each plate electrode being wound in opposition to its adjacent impedance coil of the plate electrode of adjacent audions, a divided impedance coil with the divided portions thereof wound in opposition to each other, each division thereof interposed in circuit between the source of current and the filament electrodes of said audions, a telephone transmitter associated with the grid electrodes of said audions, and an oscillatory circuit operatively associated with the plate electrode of only one of said audions.

45. 10. The combination with two associated audions and their circuits, the plate electrodes of said audions being connected in

parallel, and provided with an impedance to high frequency current therebetween, a four coil transformer and a source of current included in circuits connecting said plate electrodes and the filament electrodes of said audions, the coils of said transformer being arranged in pairs with the windings thereof opposed to each other substantially as and for the purpose described.

11. The combination with two associated audions and their circuits, the plate electrodes of said audions being connected in parallel, of circuits connecting said plate electrodes to the filament electrodes of said audions, including a source of current, and means whereby a decrease in the space current between the plate and filament electrodes of one audion causes a corresponding increase of the space current between the plate and filament electrodes of the other

audion, and an oscillatory circuit operatively associated with the plate electrodes of said audions.

12. The combination with two associated audions and their circuits, the plate electrodes of said audions being connected in parallel, of a circuit connecting said plate electrodes to the filament electrodes of said audions, including a source of current, and means included in said circuit whereby a decrease in the space current between the plate and filament electrodes of one audion causes a corresponding increase of the space current between the plate and filament electrodes of the other audion, and an oscillating circuit operatively associated with the plate electrodes of said audions.

In testimony whereof I have hereunto set my hand on this 24 day of May, A. D., 1921.

CHARLES V. LOGWOOD.
